UNITED STATES PATENT OFFICE.

CHARLES W. DEMOOY, OF CLEVELAND, OHIO, ASSIGNOR TO THE DEMOOY ELECTRIC CO., OF CLEVELAND, OHIO.

HIGH-FREQUENCY MACHINE.

1,323,354.

Specification of Letters Patent.

Patented Dec. 2, 1919.

Application filed May 12, 1916. Serial No. 97,188.

To all whom it may concern:

Be it known that I, CHARLES W. DEMOOY, a citizen of the United States, residing at #1833 East 55th St., in the city of Cleveland and State of Ohio, have invented a new and useful Improvement in High-Frequency Machines, of which the following is a specification, the principle of the invention being herein explained and the best mode in which I have contemplated applying that principle, so as to distinguish it from other inventions.

My invention pertains to high frequency machines and more particularly to an electrical apparatus of this class adapted for therapeutical purposes which comprehends an electrical stimulus or localized massage and the production of ozone.

One object of the invention is to provide a simple, compact and economical apparatus with a novel arrangement and connection of certain parts whereby advantageous results are secured with a box convenient of access and easy to carry. I especially recommend the relative arrangement of my terminal conducting points and in conjunction therewith the interposed location of a suitable dielectric. Such is designed to effect a greater efficiency with a given size or area of terminals and to require less space.

A further object is to establish ease of access for inspecting the contact points for cleaning or repair.

Another object is the provision of a unitary structure both for regulating the action between the contact points, and for covering them to simultaneously protect them against damage or short circuiting, and obviate all risk of shock to the operator.

A final object has been to so contrive the connections that when a short circuit or break in the wiring occurs, not only will the machine immediately cease to operate but the current will also stop to prevent burning of the contact points.

The essentials heretofore long since employed are a source of electrical current, an electromagnet (resonator), a pair of contacts, an induction coil, a set of terminals and a condenser. These agencies together function to produce electrical discharges

which may be utilized by concentrating their delivery from a dielectric electrode or by occasioning a gaseous reaction due to a static discharge to produce ozone. The intensification of the violet rays in either case is readily controlled. When current passes through the outer heavier wires of the induction coil lines of force are created there-around. A magnetic field is produced in which the multitude of thin inner wires rest. As the current is broken in the outside wiring an electromotive force is created occasioning a rush of current through the fine inside wiring with a tremendously high electromotive force. The resonator thereafter intermittently closes the circuit and the operation and resulting discharge is repeated.

I am well aware that a series of conducting points over a given terminal area have been before used to distribute the high frequency current, also that dielectric surfaces, usually glass, have been interposed to compensate for any tendency to produce a discharge which will not be uniformly distributed. During the energizing, the charges of opposite polarity on the conducting points which are opposed to each other, create between the ground and the terminal of the induction coil the stresses incident to the electrostatic field. My idea consists in placing the two sets of spark points in substantially vertical and parallel planes whereby the dielectric or U tube as is shown in Fig. II, may be supported between two instead of alongside only one set. Moreover, this arrangement offers the advantage of inducing a natural air current due to the generated heat and so simply but effectively ozonizes the vicinity. When the machine is utilized for discharging concentrated violet rays from a dielectric electrode, I prefer to line the hollow interior of the same with some metallic substance, having discovered one of such manufacture to be no less efficient than those having a near vacuum, and more durable because equally useful even when punctured or broken.

With the foregoing and other objects in view the invention consists of the novel construction, combination and arrangement of parts as hereinafter more specifically described and illustrated in the accompanying drawings, wherein is shown the preferred

embodiment of the invention, but it is to be understood that changes, variations and modifications can be resorted to which come within the scope of the claims hereunto appended.

Adverting to the drawings:

Fig. I is a plan of a machine embodying my invention with its cover lifted.

Fig. II is a zig-zag section on line II II 10 of Fig. I looking in the direction indicated by the arrows.

Fig. III is a vertical section taken on line III III of Fig. II.

Fig. IV is an enlarged side view of one 15 detail with a part broken away.

Fig. V is a diagram of all the electrically connected parts.

The apparatus disclosed by the drawing is contained in a suitable receptacle and 20 while the compactness of its interior arrangement constitutes one of the features of my invention the majority of the parts may be very briefly referred to because the individual function thereof has long been known 25 and used. The receptacle includes a hollow lower compartment 1 and a hollow cover 2 of nearly equal size which is hinged thereto, which carries, above, a suitable handle 3 and which is provided in its interior with a 30 number of supports adapted to hold in place the various paraphernalia usually required in the operation of a high frequency or ozonizing machine when devoted to therapeutic purposes. The compartment 1 carries 35 near its top a frame 4 through which certain parts extend by which certain other parts are suitably supported. A main either "A, C" or "D, C" electrical current cable, including wires 5 and 6 which are 40 connected with the source of current, enters the compartment 1 through an opening provided in the member 4 at one end thereof.

Near its other end the member 4 is provided with an opening 7 of considerable size 45 beneath which a conducting plate 8 is supported in an upright position. This plate carries a plurality of terminal points 9 which are preferably about equally spaced over the area thereof. Opposed to plate 8 50 on the other side of the opening 7 so as to be spaced a given distance therefrom is a similar conducting plate 10 which is also provided with a corresponding series of terminal points 11. This arrangement may be 55 seen upon inspection of Figs. II and V. The conducting plate 8 may be considered as the "ground" in its relation to the other parts to be included in the same electric circuit. A block 12 carrying a retaining pin 60 13, as shown in Fig. III, is fitted to and adapted for insertion in the opening 7. This block 12 carries in any approved manner a depending dielectric U tube customarily composed of glass and open at one end.

65 The disposition of the U tube 14 when the

block 12 is in place is substantially midway between the terminal points 9 and 11 such that the ozone created by the high frequency discharges thereacross may be, to a certain extent, held in suspense by the oil solution contained in the bottom of the tube. According to my invention the compartment 70 is provided, underneath the U tube 14, with a series of openings 15 through which a natural current of air is caused to rise owing to the generation of heat thereabove. Such a current serves to circulate and distribute ozone for direct inhalation when desired. The general disposition of the contact points 9 and 11 with relation to the upright tube 14 effects a considerable saving 75 in space and increases the facility of assemblage as well as efficiency in operation.

Between the openings for the insertion of the wires 5 and 6 and the opening 7, the member 4 is provided with another opening 16 through which certain parts of the electromagnet 17 which is supported therebelow, extend. Included among such parts is a resilient member 18 carrying a contact 80 point 19 which is adapted to vibrate in the usual way when the electromagnet becomes energized as will hereinafter become evident. Placed in one corner of the receptacle I is a condenser 20 of any approved type 85 as appears in Fig. II. The requisite induction coil 21 is also represented in this figure, its lines being dotted because in front of the plane on which the section is taken.

The manner in which I connect the condenser 20 with the rest of the system or circuit constitutes another feature of my invention, the explanation of which will, however, more logically occur farther on in this 90 description.

Mounted to one side of the contact point 95 19 which is disposed upon the member 4 is a bracket 22 to which one end of a frame 22 is hinged. This frame extends over contact 19 and carries a pair of flanges 23 depending on each side thereof so as to inclose the contact 19 when the frame 22 is swung downwardly. In this latter position another contact 25 carried by another resilient member 24 is adapted to come into superposition 100 in opposition to the contact 19. The disposition of the contacts 19 and 25 with regard to each other may be effected by means of a thumb screw 26 which also simultaneously secures the frame 22 to the 105 member 4 as may be readily perceived upon inspection of either Figs. II or IV. Loosening of the screw 26 will permit the frame 22 to be swung upwardly, thus separating the points 19 and 25 and readily permitting 110 the inspection thereof. When on the other hand, the frame 22 is secured in place its flanges 23 effectually hinder access of an operator's fingers to the contacts whenever 115 the apparatus is energized.

Directing attention now to the diagrammatic view seen in Fig. V, in order to comprehend the manner of effecting electrical connection between the essential parts, it will be noticed that after the current has passed through the wire 6, through the electro-magnet 17, member 18, contacts 19 and 25 and member 24, it is enabled to continue along a wire 27 leading to an ozone switch 28; thence along the wire 29 to an induction coil 21, pass along a wire 30 and out by means of wire 5. In thus following the current around it becomes obvious that the condenser 20 is connected in parallel with the contacts 19 and 25 by means of wires 31 and 32 which lead to opposite sides of the switch 28 and in this manner the condenser 20 is enabled, on occasion, to act as a shunt and compensate by permitting leakage therefrom. In other words such condenser takes care of any unusual pulsations by equalizing the potential at the points 19 and 25, thereby preventing the burning of the latter. For example, should a short circuit or break in the wiring occur anywhere the induction coil would be cut out of the circuit thus greatly increasing the potential on one side which if allowed to run back through the primary 17 would occasion a damaging heat generating flash at the contact points. As wired by me, the condenser 20 functions in the event of either happening just mentioned and acts as a shunt to save the points and stop the machine. The operation of a machine of the character described is ordinarily such that when the current is broken, owing to pulsations of the electromagnet, the high potential set up is sufficient to run through the wire 33 to the ground and from there jump across and be led back by the wire 34.

The flow of the current as thus far considered under varying conditions has referred to the ozonizing unit of my machine. When it is desired to effect an application to the body of violet-rays the switch 28 is thrown out and current carried instead from the wire 27 to the wire 35 thence through the other or high frequency switch 36 along the wire 37 through another induction coil 38 and back to the wire 5 by means of the conductor 39. It is primarily when the machine is so utilized for effecting high frequency discharges from a manipulated dielectric electrode that the condenser 20 is intended to function as already described because a fracture is most likely to occur and occasion a short circuit owing to a repeated twisting and bending of the cable which carries the wires 37 and 39 as illustrated in Fig. I.

I claim:

1. A high frequency machine comprising agencies operatively connected for delivering high frequency discharges, said agencies

including a spring controlled contact point and another contact point movably carried for juxtaposition with reference to the first, and means for actuating said movable contact point, and adapted to completely cover both points during the energizing of the machine whereby to preclude access of the operator thereto. 70

2. A high frequency machine comprising agencies operatively connected for delivering high frequency discharges, said agencies including an upwardly directed spring controlled contact point and another contact point movably carried for juxtaposition with reference to the first, and a hinged member and having side flanges, said movable contact point being carried between said flanges, and means for adjustably securing the free end of said member in which position the said flanges inclose both contact points for the purpose specified. 75

3. A high frequency machine comprising agencies electrically connected for delivering high frequency discharges, said agencies including a pair of contact points, a support, and a member movably carried by said support, one of said points being mounted upon said support and the other upon said member, whereby said points may be widely separated for cleaning purposes. 80

4. A high frequency machine comprising agencies electrically connected for delivering high frequency discharges, said agencies including a pair of contact points, a support, and a member movably carried by said support, one of said points being mounted upon said support and the other upon said member, said member carrying a flange adapted to inclose said points when in operative proximity to each other. 85

5. A high frequency machine comprising agencies for delivering high frequency discharges and including; an induction coil, an electro-magnet, a condenser and a pair of relatively movable contact points, all electrically connected, a support for all of said agencies, and a frame hinged to said support and carrying one of said contact points whereby an unobstructed inspection of each contact point is permitted. 90

6. A high frequency machine comprising a support and agencies carried by said support for delivering high frequency discharges, said agencies including; an induction coil, an electromagnet, a condenser, a vibrating member, a contact thereon, a movable frame, and another contact point attached to said frame, all of said agencies being electrically connected, said contacts being adapted to come into juxtaposition. 100

7. A high frequency machine comprising a support and agencies carried by said support for delivering high frequency discharges, said agencies including; an induction coil, an electro-magnet, a condenser, a 110

vibrating member, a contact thereon, a frame inounted for movement over said contact, and another contact point attached to said frame, all of said agencies being electrically connected, said contacts being adapted to come into juxtaposition and means for securing said frame so as to place

said contact which is attached thereto in a predetermined position of proximity to the other contact.

Signed by me, this 28th day of April, 1916.

CHARLES W. DEMOY.
